UNITED STATES PATENT OFFICE

2,547,073

SKI RECLINING SEAT

Anton Bueler, Schwyz, Switzerland

Application May 11, 1948, Serial No. 26,336
In Switzerland December 29, 1947

3 Claims. (Cl. 155—1)

1

The present invention relates to a folding ski reclining seat, which will enable the winter sportsman to construct a comfortable reclining chair anywhere by using his skis and ski-sticks.

In order to make this possible for the sportsman, it was necessary to design the parts of a reclining chair, i. e. for instance a suitably wide and long strip of cloth and two supporting bars, to fold together in such a way that they then gave a very small package with very little weight. In addition to that, it was necessary to create an arrangement for fixing the upper supporting rod which would ensure safe lying or sitting in the reclining chair, without using any clamping elements.

Some forms of execution of the object matter of the invention are given by way of example in the accompanying drawing, in which:

Fig. 1 shows the reclining chair rolled together,

Fig. 2 the erected reclining chair in side view, and

Fig. 3 is a plan view of the erected chair.

Figs. 4 and 5 show parts of an upper cross bar, partly in section,

Fig. 6 shows the upper cross bar covered by cloth and laid-up;

Fig. 7 shows, in perspective, a top portion of the reclining seat,

Fig. 8 shows in elevation, a modified hollow collapsible cross stick with parts in section, and

Figs. 9 and 10 are sections thereof on lines IX—IX and X—X of Fig. 8,

Fig. 11 shows the extended bar of Fig. 8 in a side view.

In Figs. 2 and 3 the reference numerals 1 and 2 refer to the skis and 3, 4 to the ski-sticks. The skis 1 and 2 are set parallel and inclined upwards. With the lower end they rest, for instance, in snow, and near the upper end they are suspended in the loops 6 and 7 of the ski-sticks 3 and 4. The forks 14, 15 provided at both ends of a bar 5 engage over the skis at the points where the skis and the ski-sticks cross, and thus determine the distance apart of the skis at the top. The bar 5 is composed of several parts, and at both ends of the middle part 8 a pliable supporting element 10 is fixed (strap, belt, cord, or the like). This element is fixed to each of the loops 11 at the points of the skis. These loops 11 engage on the points of the skis and transmit to the skis the load caused by sitting or lying. The bar 5 is composed of the parts 8 and 9, connected together by the link 12 articulated to them. Over the joints thus made, a bush 13 is pushed, where-

2

by the parts 8 and 9 are rigidly connected together, resistant to bending. At each of the two ends of the parts 9, one of the above-mentioned forks 14, 15 is provided, engaging loosely over the skis 1 and 2 (Figs. 4 and 5). The seating cloth 16 is fixed at one end to the bar 5 and at the other end to the bar 17. The bar 17 is also formed of collapsible parts 8 and 9 and its joints are also rendered rigid and resistant to bending by bushes 13 being pushed over them. The bar 17 is laid loose on the skis, so that, sliding loose on them, it automatically suits the cloth 16 to the momentary position of the body when lying or sitting.

15 In order to hold the ski sticks securely and to ensure the reclining seat being steady, cords 25 and 26 are provided, serving as stays.

The sportsman winds the cloth 16 onto the folded-up bars 5 and 17, so that a small bundle 20 about 21 cm. long is made, which can easily be carried in the pocket. The bundle may be held together with a strap (Fig. 1).

In Figs. 8 to 11 an execution of the bars 5 and 17 is illustrated. Here tubular parts 20, 21 and 22 made of suitable material are adopted. The tubular parts 20, 21 and 22 have partial higher and lower places (see Figs. 8, 9 and 10), which ensure secure fixing when in the drawn-out position (Fig. 11). The tubular parts 20 and 22 are slotted at their ends, so that they engage the skis fork-like, just as the bar 5 does. The rest of the composition of the reclining seat is effected in the sense already described above.

What I wish to secure by U. S. Letters Patent is:

1. In a seat, designed to be borne between two spaced skis supported each inclined and with its point up by a ski pole, in combination, a bar disposed between said skis and having near its end 40 means for abutting against the inner edge of each ski and having means for sliding over a ski surface adjacent the edge, suspension means connected to said bar and to said points of the skis for restraining downward sliding of said bar, strap means connecting each end of said bar with the diagonally opposite ski pole for stabilizing the positioning of said bar relative to the ski and pole supports, a flexible seat portion extending downwardly from said bar, and a second bar 45 connected to the lower end of said seat portion and slidably supported on said ski surfaces.

2. In a seat as claimed in claim 1, together with, each of said bars composed of a plurality of links interconnected by pivots, and reinforcing 55 sleeves each for a pivot and each sleeve being

slidable on links between an inactive position wherein said links may be folded against each other and an active position wherein each sleeve surrounds a pivot to maintain in alignment the links adjoining said pivot.

3. In a seat as claimed in claim 1, together with, each of said bars composed of a plurality of tubular telescopic links each having means for releasably latching onto an adjoining link.
